Primary Examiner — Marie D. Fast Horse*(74) Attorney, Agent, or Firm* — Boyle Fredrickson, S.C.**CLAIM**

The ornamental design for a fan, as shown and described.

DESCRIPTION

FIG. 1 is an isometric view of a fan in accordance with the present invention;

FIG. 2 is a front elevational view of the fan of FIG. 1;

FIG. 3 is a rear elevational view of the fan of FIG. 1;

FIG. 4 is a side elevational view of a first side of the fan of FIG. 1;

FIG. 5 is a side elevational view of a second side of the fan of FIG. 1;

FIG. 6 is a top plan view of the fan of FIG. 1; and, FIG. 7 is a bottom plan view of the fan of FIG. 1.

The broken lines in the drawings depict portions of the fan that form no part of the claimed design.
